UNITED STATES PATENT OFFICE.

JEREMIAH R. KNAAPP, OF NORWALK, OHIO, ASSIGNOR OF ONE-HALF TO
SAMUEL C. TYLER, OF NORWALK, OHIO.

GAME.

SPECIFICATION forming part of Letters Patent No. 757,470, dated April 19, 1904.

Application filed August 17, 1903. Serial No. 169,813. (No model.)

To all whom it may concern:

Be it known that I, JEREMIAH R. KNAAPP, a citizen of the United States, residing at Norwalk, in the county of Huron and State of Ohio, 5 have invented a new and useful Game, of which the following is a specification.

This invention relates to game-boards, and more particularly that class employing surface projectiles.

10 The object is to provide a game that is novel, interesting, and requiring skill, as well as having elements of chance, thereby making it attractive.

15 The preferred form of construction is illustrated in the accompanying drawings, wherein—

Figure 1 is a perspective view of a game-board constructed in accordance with the present invention. Fig. 2 is a perspective view of 20 a cue employed in connection therewith. Fig. 3 is a cross-sectional view through the board. Fig. 4 is a longitudinal sectional view.

Similar reference-numerals indicate corresponding parts in all the figures of the drawings.

In the embodiment illustrated the board comprises a bottom 5, supported by transverse sleepers 6 and having side and end walls 7 and 8 that extend above the bottom. The 30 upper face of the board is provided with a centrally and longitudinally-disposed playing-field 9, which is concaved transversely, as shown. Alleys 10 are located on opposite sides of the playing-field and are also located longitudinally of the board. The field and alleys are defined by longitudinally-disposed bars 11, extending from end to end of the board and secured to the walls 8 in any suitable manner. These bars 11 are elevated 35 above the surface of the board and constitute obstructions for larger balls employed in playing the game, though permitting the passage of smaller balls, as is hereinafter more fully explained.

40 The playing-field is provided with a series of transversely-disposed grooves 12, the ends of which extend beneath the bars 11. These grooves are provided with ball-receiving pockets 13, each being preferably provided with

one and said pockets being disposed in staggered relation, as illustrated in Fig. 1. Located in one end of each alley is a longitudinally-disposed partition 14, that subdivides said end into pockets 15, the outer ends of which are open. The opposite ends of each alley 55 contains a return-spring 16, that is preferably formed of a doubled sheet of resilient material secured to the adjacent end wall.

Each player is provided with a ball 17, that is of sufficient size to be prevented by the bars 60 11 from passing between the alley and field. Each player, furthermore, has a small ball 18 that can pass beneath the bars 11, while cues, as 19, of any suitable structure are also provided. While it will be understood that games 65 of various kinds can be played upon the board, a very simple form may be described as follows: One of the players places his small ball 18 in one of the pockets 15 of the alley and the large ball at the end of the partition 14, 70 as illustrated in the upper right-hand corner of Fig. 1. The other player places his large ball 17 at his margin of the field, the margins being smooth and provided with sockets 20, as illustrated. The player whose balls 75 are in the alley first propels the large ball to the opposite end of the same, where it will strike the return-spring and rebound. During this return the smaller ball is shot by means of the cue and if it properly strikes 80 the other ball will be deflected under the bar 11 and onto the playing-field, perhaps, in one of the grooves. In case of this successful play while the ball 18 is moving over the field the other player attempts by shooting 85 his large ball 17 to strike the smaller one of his opponent, and if successful the player whose ball 18 is upon the field fails to score. If, however, the ball 18 reaches one of the pockets 13 without being struck, a score is 90 made, which can be regulated as desired. If, however, the opponent prevents the scoring or if the small ball 18 fails to leave the alley under the conditions described, the opponent has the right to play. Of course the rules 95 may be varied and changed as desired. It will be apparent, however, that an interesting game can be played, for while there is

considerable chance a comparatively high degree of skill is required to send the ball 18 into the proper groove by means of the ball 17 and also on the part of the opponent to 5 prevent said ball 18 from scoring.

From the foregoing it is thought that the construction, operation, and many advantages of the herein-described invention will be apparent to those skilled in the art without 10 further description, and it will be understood that various changes in the size, shape, proportion, and minor details of construction may be resorted to without departing from the spirit or sacrificing any of the advantages of 15 the invention.

Having thus described my invention, what I claim as new, and desire to secure by Letters Patent, is—

1. In a game-board, the combination of a 20 playing-field, of an alley located alongside the field and of sufficient width to permit the play therethrough of different sizes of balls, said alley at one end having a return-spring arranged to cause the rebound of a ball striking 25 the same, and an obstruction defining the boundary between the alley and field, said obstruction being located above the surface sufficiently to permit the passage thereunder of 30 the smaller ball and retain the larger one in the alley.

2. In a game-board, the combination with a playing-field, of an alley located longitudinally alongside the field and of sufficient width to permit the play therethrough of different sizes 35 of balls, said alley having at one end a longitudinally-disposed partition forming a reduced ball-receiving pocket and having at its other end a return-spring arranged to cause the rebound of a ball striking the same, and 40 a bar defining the boundary between the alley and field, said bar being located above the surface sufficiently to permit the passage thereunder of a small ball and to retain a larger one in the alley.

45 3. In a game-board, the combination with a transversely-concaved playing-field provided in its surface with a series of ball-receiving pockets, of a straight alley located alongside the field and having a closed outer side and 50 closed ends, and a bar defining the boundary between the alley and field, said bar being arranged above the surface to permit the passage thereunder of balls of a predetermined size.

55 4. In a game-board, the combination with a playing-field, of an alley, and a bar located between the alley and field and elevated above the surface thereof, said field being provided

with a plurality of transversely-disposed grooves extending from one side of the field 60 beneath the bar and having ball-receiving pockets.

5. In a game-board, the combination with a playing-field, of an alley located alongside the playing-field and of sufficient width to permit 65 the free passage of balls of different sizes, and an obstruction defining the boundary between the alley and field, said obstruction being located above the surface of the same sufficiently to permit the passage thereunder of the smaller 70 ball and at the same time retain the larger one in the alley, said playing-field having grooves in its surface that extend from points contiguous to the obstruction.

6. In a game-board, the combination with a 75 centrally-disposed transversely-concave playing-field, of alleys located on opposite sides of the field, and bars located longitudinally of the board and spaced above the surface thereof, 80 said bars defining the field and alleys.

7. In a game-board, the combination with a centrally-disposed playing-field, of alleys located on opposite sides thereof and at the sides of the board, longitudinally-disposed bars defining the alleys and field and elevated above 85 the surface of the board, said field having transversely-disposed grooves extending beneath the bars and having a series of pockets located in staggered relation.

8. In a game-board, the combination with a 90 transversely-concaved playing-field, of alleys arranged longitudinally along the opposite sides of the field, said alleys having closed ends and outer walls, and bars defining the opposite side walls of the field and the inner walls 95 of the alleys, said bars being elevated above the surface to permit the passage thereunder of balls of a predetermined size.

9. In a game-board, the combination with a centrally-disposed transversely-concave playing-field, having transverse grooves provided 100 with pockets, of alleys located at the sides of the field, longitudinally-disposed bars elevated above the surface of the board and defining the field and alleys, a longitudinally-disposed 105 partition located in one end of each alley, and a return-spring arranged in the opposite end of each alley.

In testimony that I claim the foregoing as my own I have hereto affixed my signature in 110 the presence of two witnesses.

JEREMIAH R. KNAPP.
